UNITED STATES PATENT OFFICE.

WILLIAM J. HALLIWELL AND THOMAS DONOHUE, OF PATERSON, NEW JERSEY.

FIRE-LIGHTING ATTACHMENT FOR STEAM-ENGINES.

SPECIFICATION forming part of Letters Patent No. 496,156, dated April 25, 1893.

Application filed January 16, 1893. Serial No. 458,614. (No model.)

To all whom it may concern:

Be it known that we, WILLIAM J. HALLIWELL and THOMAS DONOHUE, both of Pater-
son, in the county of Passaic and State of New Jersey, have invented a new and useful Im-
provement in Fire-Lighting Attachments for Steam-Engines, of which the following is a
specification.

Our invention relates to an improvement
in fire lighting attachments for steam engines
and more particularly to attachments for
steam fire engines in which provision is made
for starting a flame by the chemical combi-
nation of certain ingredients.

15 A practical embodiment of our invention
is represented in the accompanying drawings
in which—

Figure 1 represents in side elevation a por-
tion of a steam fire engine as commonly con-
structed. Fig. 2 is an enlarged view in lon-
gitudinal vertical section of the fire lighter
attachment. Fig. 3 is a view of the same in
end elevation. Fig. 4 is a top plan view of
the same, and Fig. 5 is a modified form of le-
ver for operating the lighter.

The form in which we have chosen to illus-
trate our fire lighter is that adapted to use in
connection with the steam fire engine as com-
monly built in which a spray pipe extends
30 down the side of and under the bottom of the
boiler and serves as a convenient support for
securing the fire lighter thereto.

In the accompanying drawings A repre-
sents the boiler of the steam fire engine and
35 a the spray pipe above referred to. A bent
supporting arm B is provided at one end with
a half bearing b adapted to receive the spray
pipe at the point where it turns horizontally
40 under the boiler and a removable half bear-
ing b' is adapted to be secured to the arm B
upon the opposite side of said spray pipe and
drawn snugly into contact with the pipe by
draw bolts b''. The opposite end of the sup-
porting arm B has pivotally secured thereto
45 to swing in a horizontal plane a supporting
trough and bracket C. The connection of the
bracket C with the arm B is preferably made
by extending a pivotal bolt c through the two
parts and providing the pivotal bolt with a
50 tail nut c' by means of which the bracket may
be clamped in any desired horizontal adjust-

ment. The bracket C is provided with a pair
of supporting standards D, D' between which
a casing or pocket E is journaled, preferably
by means of a pair of laterally extending 55
trunnions e loosely mounted in bearings d, d'
in the arms D and D'. From the position of
the case or pocket E the bracket is provided
with a trough c² which extends on a decline
to a receptacle F secured to a depending lip 60
at the trough end of the bracket.

The pocket or casing E is adapted to receive
a bottle containing some suitable chemical,
as for example sulphuric acid, and the recep-
tacle F may in such case contain a mass of 65
cotton waste saturated to a greater or less ex-
tent with oil. The bottle is kept normally
covered by means of a combined shield and
stopper G which is pivotally secured at its
70 upper end to the upper ends of the standards
D, D' and extends thence over the mouth of
the bottle where it may be provided with
some suitable yielding pad g for effectively
closing the mouth of the bottle and thence
75 extending downwardly and outwardly toward
the trough c².

An operating cord H leads from a lug or
ear e² on the casing E up to one arm of a rock-
ing lever I and from the opposite arm of said
lever operating cords h and h' lead forward 80
and rearward into position to be readily
grasped by either the engineer or driver.

The operation is as follows: When it is de-
sired to start the fire in the boiler, as for ex-
ample in connection with a steam fire engine, 85
when the engine reaches a point sufficiently
near a fire to allow time for getting up steam
during the time of travel from that point to
the fire, either of the cords h or h' may be
pulled, the lever I thereby rocked and by its 90
connection with the pivoted casing E the casing
and the bottle therein will be tilted over with
its mouth toward the trough c². As the bot-
tle tilts it will free the stopper from its mouth
and the liquid will be deflected by the shield 95
G into the trough and upon reaching the cot-
ton waste in the receptacle F will produce a
flame which will light the fire in the boiler.

The connection of the bracket C with the
arm B is such that the receptacle F may be 100
swung outwardly from under the boiler out of
the way when not in use or it may be removed

altogether from the arm B and the arm B may be removed at pleasure from the spray pipe.

While we have shown the attachment as connected to the spray pipe, we do not wish 5 to be understood as limiting ourselves to such a support only as differently constructed engines might require various modifications in the support for the arm B.

What we claim is—

- 10 1. A fire lighter comprising a swinging bracket, a receptacle in which the flame is to be produced fixed to the swinging bracket, a tilting receptacle for a chemical, a conduit leading from the tilting receptacle to the receptacle in which the flame is to be produced, and means for tilting the chemical containing receptacle at pleasure, substantially as set forth.
- 15 2. In combination a suitable supporting arm, a swinging bracket secured to the arm and adapted to swing underneath and away from the fire chamber of a boiler, a receptacle

fixed to the swinging bracket for containing the substance to be set on fire, a tilting chemical receptacle carried by the bracket, and an 25 operating cord leading from the tilting receptacle to within convenient reach of the operator, substantially as set forth.

3. The fire lighter comprising a suitable support, a swinging bracket secured in horizontal adjustment to the support and provided with a trough, a receptacle fixed beneath the outlet end of the trough, a tilting casing or pocket adapted to receive a bottle, a swinging shield forming normally a stop- 30 per to the bottle when in position within the pocket, and means for tilting the casing or pocket at pleasure, substantially as set forth.

WILLIAM J. HALLIWELL.
THOMAS DONOHUE.
